GOLF TRAINING APPARATUS

Robert Crowley, North Quincy, Mass.

Application June 4, 1938, Serial No. 211,745

2 Claims. (Cl. 273—35)

My present invention is a novel and improved golf training apparatus, and is directed to improve and perfect the type of device for teaching and practicing golf illustrated and described in my prior and copending application Ser. No. 195,499 filed March 12, 1938.

Important objects of the present invention are to simplify the construction of my said prior apparatus, to improve the adjustability and, in general, to render such devices more practical for use, retaining all the advantageous features in a more economical structure, with capacity for fuller adjustments.

A further and important feature consists in protecting certain parts of the apparatus from damage or injury to the clubs of the player using the device; and for this purpose I enclose, encase, or cover the parallel guide bars with yielding and protecting material, such as rubber, so that accidental striking of the same by the club during the use of the device will cause no damage or injury to the club itself nor to the parallel bars. Other parts of the apparatus can be similarly protected, if desired, within the scope of my present invention.

A still further feature consists in the capacity for and adaptability of quick and rapid radial adjustment of certain of the gauges and measuring elements. Also, such radial adjustment is effected by simply loosening and tightening thumb nuts, and swinging of the gauge to the desired or predetermined mark, degree, or indication point on a protractor having an arc so marked to cooperate with a corresponding pointer on the gauge being radially adjusted in relation thereto and in relation to the rest of the apparatus.

Thus, such radial adjustments can be readily repeated with complete accuracy when the device has been adjusted to other points or when it is being assembled for use.

Other improvements, details, and advantages will be hereinafter more fully pointed out and claimed.

Referring to the drawing illustrating a preferred embodiment of my present improved apparatus,

Fig. 1 is a plan view of my device;

Fig. 2 is a cross-sectional view on the line 2—2 of Fig. 1;

Figs. 3 and 4 are side and plan views, respectively, illustrating the radial adjustment of the main gauge and bar to which it is attached;

Fig. 5 is a view on the line 5—5 of Fig. 2; and Fig. 6 illustrates a modification.

Referring to the drawing, I utilize two spaced

parallel bars 1 and 2 similar in length, size, and spacing to the corresponding parallel bars of my said prior application which are used as a double guide for the player to improve and control the swing of his clubhead when striking the ball 3, which is positioned between the parallel bars.

These bars 1 and 2 I prefer to form with a wooden or metal core 5 and a covering of rubber 6, thus providing a protecting, yielding, resilient surface for the bars 1 and 2, eliminating damage to the golf club if the same strikes either bar, and also eliminating danger of damage to the bars themselves. This feature, furthermore, imparts confidence to the player, being free from danger of damage to either the apparatus or club while practicing with the device.

Connecting the parallel guide bars 1 and 2 are a pair of adjustable link members, each comprising a solid link 7 pivoted at 8 to the cross-bar 2 and a notched link 9 pivoted at 10 to the cross-bar 1, said links being pivotally united together approximately at the center when extended to their greatest space by a pivot or bolt 12 to permit folding of these links and bringing the parallel guide bars 1 and 2 into close relationship for convenience in transporting. Preferably each member 9 extends beyond the pivot 12 and is provided with a spring clip portion 14 adapted to register with a corresponding portion 15 in the adjacent part of the link 7 to retain these two links in extended position and thus lock the parallel bars properly spaced. To effect adjustment of width between the bars 1 and 2, the series of notches in each link 9 opening on a slot 16 are adapted to slide on the shank of the retaining bolt 10 so that when said bolt is loosened slightly, the guide bar 1 may be brought closer to or further away from the companion bar 2 and held in adjusted position, any different corresponding notch in each link being used, as desired, by a retightening of the bolts 10, as will be readily understood.

Attached also on the cross-bar 2 is a gauge or guide 19, and adjacent thereto on one side is a track 17 upon which a slide 18 may travel, such slide carrying a bracket 20 to which is pivotally secured at 21 a gauge 22. Thus the gauge member 22 may be adjusted to and fro on the bar 1 to any position desired or indicated on the rule 19, and may also be swung on its pivot 21 for radial adjustment to cooperate with the stance of the player desired, or the correction in the swing for which the device may be adjusted.

Secured also to the bracket 20 is a protractor 55

25 rigidly attached thereto by the pivot bolt 21 and also by a rivet 26, which latter holds the protractor 25 firmly to the bracket. I prefer to form a series of degree marks, as indicated in Fig. 4 at 27, on the under side of the protractor 25, Fig. 4 being a plan view of this structure from underneath the apparatus, as shown in Figs. 1 and 2. This permits the operator to stand the parallel bars upwardly and adjust the gauge 22 radially while viewing the degree markings 27 and positioning them with relation to a pointer 28 affixed to the gauge 22 to secure the adjustment desired. Tightening of the wing nut 23 on the pivot bolt 21 will hold the gauge 22 in its radial position when adjusted out of the perpendicular relatively with the cross bar 2.

When it is desired to have the gauge 22 in exact ninety-degree position relatively with the cross-bar 2, I provide a removable pin or bolt 30, fitting thru a hole 31 in the center of the gauge 22 adjacent the pivot or protractor end and a corresponding hole 32 in the protractor 25, so that when the gauge 22 is swung into perpendicular relationship with the bar 2 a pin or bolt 30 may be fitted therein, as shown in Figs. 1 and 2.

The gauge 22 is formed with grooves 34 on each side to receive a pair of projecting tongues carried on the slide block 35, similar to the construction in my prior device. This block 35 carries a projecting rod 36 which may be slid over the cross bar 2 and rule 16 to determine the position of the ball 3 and, thereupon, the slide 35 may be retracted out of the way, as shown in Fig. 1, and may be held in any position to which the rod 36 is moved by tightening a thumb nut 37, which extends thru the top of the slide 35 and impinges on the rod 36. Also the slide 35 may be moved back and forth with its tongues in the grooves 34 to move it out of the way of the space between the parallel guide bars 1 and 2, as will be readily understood.

Preferably I affix center marks 38 on the bar 1, and 39 on the bar 2 which would be the zero mark of the rule 19, so that the ball 3 may be positioned with substantial accuracy centrally of the length of the parallel guides 1 and 2 independently of the use of the rod 36, if desired, as well as in cooperation therewith to locate the positioning of the golf ball 3.

Slidably secured also on the gauge 22 is a block 40 carrying a protractor 41 similar to 25 already described, which block 40 may be moved up and down to any desired position on the gauge 22 and locked in adjusted position by tightening a thumb nut 42. Pivotaly mounted on the block 40 is a member 44 adapted to swing over the protractor 41 carried by the block 40, and which pivotal member has secured thereto a cross gauge 45. Preferably this cross gauge is attached underneath the swinging member 44 and is held in any desired adjusted position thereto by a thumb nut 47. The swinging member 44 is attached to the block 40 by an upstanding rivet or bolt 48 and may be locked in position by a threaded wing nut 50 surrounding the exposed upper end of the bolt 48 and tightening the same upon the member 44 at any angle at which said member may be positioned on the block 40.

Thus the gauge 22 may be slidably adjusted on the track 17 to align the same in any desired position for the particular player with regard to the parallel guide bars 1 and 2, and may also be

radially positioned by swinging the same on the pivot 21, first removing the pin 30 if the latter is in position. Also the cross gauge 45 may be moved toward or from the parallel bars 22 by sliding the block 40, and said cross bar 45 may also be radially positioned to more accurately determine the correct or corrective stance for the feet of the player, the cross gauge 45 being ordinarily positioned for contact with the right and left toe of the player, the left foot being at one side of the gauge 22 and the right foot on the other side.

Referring to Fig. 6, I have illustrated a modification wherein I form one of the parallel bars, preferably number 2, with curved ends 51 and 52. In this form, the parallel guide bars 1 and 2 are straight and parallel for the greater part of their distance to visualize the alignment of the path of the clubhead in striking the ball 1 with the end portions of the guide 2, which is closer to the player, having the ends formed in a curve or arc which will approximate the sweep of the golf club during its swing by the player.

I find that this modification with the curved ends is desirable in many instances and is one of the features illustrated in my said prior and co-pending application, but in the present form I prefer to utilize this arc on one of the parallel guides only, substantially as shown.

I find that this provision of the curved ends aids in eliminating any undue or unconscious strain on the part of the player to make the swing of his golf club being distorted in bringing the same down between the parallel guides. Therefore, I consider this feature of substantial importance and wish to claim the same herein.

Innumerable positions and adjustments can be readily and efficiently made, and the slides 35 and 40 will ordinarily be maintained in position by gravity, the entire apparatus being resting on the floor or ground; or, of course, the thumb nuts may be tightened to retain the same in the positions to which the adjustments have been made when desired.

Thus I have provided in an extremely simple and improved construction gauges and adjustments suitable to determine, relatively with the golf ball, the stance of the player, the distance and spacing, as well as the angle and position of the feet of the player with relation to the position of the golf ball 3 to be played and for the articular stroke or club being used.

I claim:

1. A golf training and practicing apparatus of the kind described, comprising parallel guide rods supported above the ground and spaced to receive a golf ball therebetween, in combination with adjustable gauge members to facilitate the stance of the player relatively with said parallel guide rods, said rods being protected with a yielding tubular covering throughout the length of said guide rods.

2. A golf training and practicing apparatus of the kind described, comprising adjustable parallel guide rods spaced to receive a golf ball therebetween, in combination with a gauge slidably secured to one of said parallel bars and perpendicular thereto, with capacity for radial adjustment relatively with said guides, said gauge carrying a cross-gauge united thereto by radially adjustable connecting means.

ROBERT CROWLEY.
